COMBINED SLICE AND ADJUSTABLE DECKLE MECHANISM FOR FOURDRINIER MACHINE

Fernand H. Willemain, Holyoke, Mass., assignor to American Writing Paper Corporation, Holyoke, Mass., a corporation of Delaware

Application December 20, 1954, Serial No. 476,347

6 Claims. (Cl. 92—44)

This invention relates to improvements in paper making and is directed more particularly to improvements in deckle and slice mechanism at the web forming end of a Fourdrinier paper making machine.

The principal object of the invention is the provision of apparatus for the forming end of a Fourdrinier machine constructed and arranged to provide various widths of deckle relative to slice means.

It is often desired to provide a width of deckle less than that for which the paper machine is designed and to accomplish changes in width the deckle straps commonly used are moved relative to one another transversely of the machine.

It is also desired that the slice means be positioned intermediate the ends of the deckle straps but in such a case the width of deckles may be changed only by provision of a special slice for each deckle width or a slice which is adjustable transversely. In either case due to the slice arrangement there results down time of the machine which is objectionable from a cost and manufacturing standpoint.

According to the novel features of the invention there is provided at the forming end of the Fourdrinier machine, slice mechanisms disposed intermediate the ends of deckle means which is arranged in combination with the slice mechanism for adjustment of the deckle mechanism to vary the width of deckle without requiring slice changes thereby overcoming objectionable down time of the machine and complicated and costly slice mechanisms.

According to a special feature of the invention the deckle and slice mechanisms are such as to function for their intended purposes and to cooperate for deckling and sheet or web formation without the deckle mechanism being dependent on the slice mechanism.

In a broad way slice mechanisms extend across the machine for the formation of a web or sheet of maximum width deckle means rearwardly and forwardly of the slice mechanism is arranged for changing the width deckle at any time.

According to novel features of the invention the deckle means is not only adjustable transversely but is adjustable vertically relative to the wire while the slice mechanism is independently adjustable relative to said wire.

The construction of the invention is associated with the forming end of the Fourdrinier machine as the opposite side walls may be established or with walls provided with the slice and deckle means.

All of the above cited objects I accomplish by means of such structure and relative arrangement of parts thereof, as will fully appear by a perusal of the description below and by various specific features which will be hereinafter set forth.

To these above and other ends and with the foregoing and various other and ancillary features and advantages and objects of my invention as will become more readily apparent as the description proceeds, my invention consists in certain features of novelty, in a mode of operation, and in the combination, organization, and arrange-

2

ment of parts as will be hereinafter more particularly pointed out in the claims hereunto annexed and more fully described and referred to in conjunction with the accompanying drawings wherein:

- 5 Fig. 1 is a side elevational view of slice and deckle apparatus embodying the novel features of the invention;
Fig. 2 is a sectional elevational view on the line 2—2 of Fig. 1;
Fig. 3 is a sectional elevational view on the line 3—3 of Fig. 1;
10 Fig. 4 is a plan view of the front side of the apparatus shown in Fig. 1;
Fig. 5 is a sectional elevational view on the line 5—5 of Fig. 1;
15 Fig. 6 is a longitudinal sectional elevational view on the line 6—6 of Fig. 4;
Figs. 7 and 8 are side and end elevational views of the secondary deckle;
Fig. 9 is a sectional elevational view on the line 9—9 of Fig. 1;
20 Fig. 10 is a partial elevational view of the side wall of the apparatus showing the sealing strip associated therewith;
Fig. 11 is a sectional elevational view on the line 11—11 of Fig. 1;
25 Fig. 12 is a transverse sectional elevational view on the line 12—12 of Fig. 1; and
Fig. 13 is a diagrammatic plan view to show the relationship of the deckles and slices of the apparatus.
30 Referring now to the drawings more in detail the novel features of the invention will be fully described.
As in Fig. 1 a breast roll 2, a series of table rolls 4 and the Fourdrinier forming wire 6 are shown by dash lines. There are transversely spaced side walls 10 and
35 an apron 12, all of which are usual in a Fourdrinier paper making machine. The rear ends of the side walls 10 are connected to end walls such as 14 and a stock inlet is represented by 16.
Elongated extensions 18 are secured at the forward
40 outer ends of the side walls 10 and opposite ends of transverse struts 20 are secured therein to provide strength and rigidity to the structure.
A pair of elongated primary transversely adjustable deckle members 22 extend forwardly between the side walls 10 from the inlet. These members 22 have lower feet 24 for overlying the moving Fourdrinier wire. Said members will be formed from material not likely to injure or cause wear to the wire. Various plastic materials will be suitable for the purpose. The primary deckle members 22 are slidably adjustable on transverse rods 26 which are threaded. Nuts 23 on said rods clamp the members in adjusted positions.
Rails 30 which may be in the form of channels are secured along upper edges of the side walls 10. Brackets 32 on the rails 30 of opposite walls 10 have depending arms 34 to which the rods 26 are secured, see Fig. 9. Jack screws 36 in threaded engagement with the brackets 32 have lower ends which abut the rails. Lock nuts 38 lock the screws in place. The jack screws may be rotated to raise or lower members 22 to position the under sides thereof as may be desired relative to the wire.
The primary deckle members may be adjusted transversely to provide the desired width of deckle and are locked in place by the nuts 23 on the rods 26.
45 A rigid slice 42 extends transversely between the side walls 10 forwardly of the deckle members 22 and is suspended vertically from a support 44. Said support has opposite ends thereof secured to brackets 46 which are similar to the brackets 32 described. These brackets 46 have adjusting screws 48 resting on the rails 30 to facilitate raising and lowering the slice for adjustment of its lower edge relative to the wire.
50
55
60
65
70

A transverse upper strut 50 has opposite ends secured to upper sides of the rails 30. Supports, such as 52, are fixed to opposite ends of said support 50 and are provided with elongated slots 54. Rods 56 threaded on upper ends are slidable along the slots and depend from member 52. Nuts 58 in engagement with the rods lock the rods in various positions of vertical adjustment.

Intermediate or secondary deckle mechanisms are carried by lower ends of the rods 56 such as indicated by 60, in Figs. 7 and 8. Each said slice includes a pair of members 62 and 64 which are relatively slidable on pins 66 and are yieldably urged apart by a spring 68. These parts 62 and 64 are provided with resilient sealing pads 70 and 72.

The pad 70 abuts the rigid slice 42 and the pad 72 abuts an angularly disposed flexible slice 76. A plate 78 carried by a side of slice part 62 overlaps a side of slice part 64 so as to seal the space between the slice parts. At the same time the deckles are sealed to the slice members. The pads 70 and 72 may be formed from sponge rubber, 20 rubber composition or the like.

By moving the rods 56 along members 52 the secondary deckles may be moved towards one another to vary the deckle.

The slice 76 has its upper end secured at 80 to a leg 82 of a transverse slice carrier 84. Threaded rods 84' are pivoted at points 83 along the lower lip of the slice 76 and adjusting wheels 83' on the rods 86 are manipulated to adjust the lower lip of the slice 76 which is flexible for that purpose.

Brackets 77 on the rails 30 have inner legs 79 depending downwardly inside of the side walls to which opposite ends of carrier 84 are secured. Threaded rods 81 in engagement with the brackets 77 rest on the rails so as to adjust the said brackets up and down and thereby adjust the slice relative to the wire.

Elongated deckle rulers 100 extend forwardly from the flexible slice 79. Supports 102 are carried by the extensions 18 and extend outwardly and then return inwardly in the form of elongated supports 104. Links 106 have 40 bearing members 108 slidable on the supports 104 and the rulers 100 are connected to lower ends of the links 106.

The links may be moved along the supports 104 to adjust the rulers transversely. Binding screws 110 in threaded engagement with the bearing members bind 45 said bearing members in adjusted positions.

The supports 102 may be pivotally connected to the extensions 18 to permit longitudinal movements of the rulers 100 in adjusting the parts.

Sealing strips 120 of rubber or the like are provided at the lower end of the side walls 10 and are held in place by clamp strips 122 and screws 124 extending into the side walls. Other sealing strips 126 are clamped to the rulers 100 by clamp strips 128 and screws 130. Lower edges of the sealing strips act as seals on the Fourdrinier wire.

It will be observed that the slice mechanisms extend transversely between the walls 10 and are adjustable up and down relative to the wire. The primary and secondary deckle members and the deckle rulers are adjustable transversely and independently of the slices whereby the desired width of deckle may be obtained without changes in the slice mechanism. Adjustments may be made easily and readily without disassembling the machine and in providing for the desired deckle the deckle members and rulers may be adjusted to the desired alignment as indicated diagrammatically in Fig. 13.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description and all modifications and variations as fall within the meaning and purview and range

5 of equivalency of the appended claims are therefore intended to be embraced therein.

What it is desired to claim and secure by Letters Patent of the United States is:

1. Combined slice and deckle mechanism for Fourdrinier paper machine comprising in combination, a structure including elongated transversely spaced substantially vertical side walls and an inlet for paper stock at the rear end thereof, a pair of elongated transversely spaced primary deckle shoes extending forwardly from said inlet, a transversely disposed rigid slice forwardly of said primary shoes, a pair of transversely spaced secondary deckle shoes forwardly of said rigid slice, a transversely disposed flexible slice forwardly of said secondary shoes having a flexible lip, a pair of elongated transversely spaced deckle edge rulers extending forwardly from said flexible slice, separate means connecting said primary and secondary shoes of the pairs thereof and said pair of deckle rulers to said structure arranged for relative transverse adjustment of the shoes of the pairs thereof and of the said rulers of the pair thereof towards and away from one another and longitudinal alignment of said shoes and rulers.

2. Combined slice and deckle mechanism for Fourdrinier paper machine comprising in combination, a structure including elongated transversely spaced substantially vertical side walls and an inlet for paper stock at the rear end thereof, a pair of elongated transversely adjustable primary shoes forwardly of said inlet, a transversely disposed rigid slice forwardly of said primary shoes extending between said side walls, a pair of secondary transversely adjustable deckle shoes forwardly of said rigid slice, a transversely disposed flexible slice forwardly of said secondary shoes extending between said side walls having a flexible lower lip, a pair of elongated deckle edge rulers extending forwardly from said flexible slice, separate means connecting said pairs of primary and said secondary shoes and said pair of deckle rulers to said structure arranged for independent relative transverse adjustment of the shoes of the pairs thereof and of the said rulers of the pair thereof towards and away from one another and for longitudinal alignment of said shoes and rulers, and separate means connecting said rigid and flexible slice to said structure arranged for independent vertical adjustment of said slices relative to said structure.

3. Combined slice and deckle mechanism for Fourdrinier paper machine comprising in combination, a structure having opposite transversely spaced vertical side walls and a stock inlet at the rear end thereof, a pair of elongated transversely spaced relatively adjustable primary deckle shoes extending forwardly from said inlet, a vertical rigid transversely disposed slice forwardly of said primary shoes extending between said walls, a pair of secondary transversely spaced relatively adjustable deckle shoes forwardly of said rigid slice, a transversely disposed flexible slice forwardly of said secondary shoes extending between said walls having a lower transverse flexible lip, a pair of elongated transversely spaced relatively adjustable deckle rulers extending forwardly from said flexible slice, separate bracket means supporting said primary shoes from said walls arranged for up and down vertical adjustment of said shoes and transverse adjustment thereof towards and away from one another and longitudinally of said rigid slice, other bracket means supporting said slices from said walls arranged for independent up and down vertical adjustment thereof, and means for adjusting the flexible lip of the flexible slice.

4. Combined slice and deckle mechanism for Fourdrinier paper machine comprising in combination, a structure having opposite transversely spaced vertical side walls and a stock inlet at the rear end thereof, a pair of elongated transversely spaced relatively adjustable primary deckle shoes extending forwardly from said inlet, a vertical rigid transversely disposed slice forwardly of said primary shoes extending between said side walls, a pair

of secondary transversely spaced relatively adjustable deckle shoes forwardly of said rigid slice, a transversely disposed flexible slice forwardly of said secondary shoes having a lower transverse flexible lip, a pair of elongated transversely spaced relatively adjustable deckle rulers extending forwardly from said flexible slice, separate bracket means supporting said primary shoes from said walls adapted and arranged for up and down vertical adjustment of said shoes and transverse adjustment thereof towards and away from one another and longitudinally of said rigid slice, other bracket means supporting said slices from said walls arranged for independent up and down vertical adjustment thereof, means for adjusting the lip of the flexible slice, and separate means supporting the shoes of the secondary pair thereof from said walls adapted and arranged for adjustment of said shoes up and down and towards and away from one another and longitudinally of said slices.

5. Combined slice and deckle mechanism for Fourdrinier paper machine comprising in combination, a structure having opposite transversely spaced vertical side walls and a stock inlet at the rear end thereof, a pair of elongated transversely spaced relatively adjustable primary deckle shoes extending forwardly from said inlet, a vertical rigid transversely disposed slice forwardly of said primary shoes extending between said side walls, a pair of secondary transversely spaced deckle shoes forwardly of said rigid slice, a transversely disposed flexible slice forwardly of said secondary shoes extending between said walls having a transverse flexible lip, a pair of elongated transversely spaced relatively adjustable deckle rulers extending forwardly from said flexible slice, bracket means supporting said primary shoes from said walls arranged for up and down vertical adjustment of said shoes and transverse adjustment thereof towards and away from one another and longitudinally of said slice, bracket means supporting said slices from said walls arranged for independent up and down vertical adjustment thereof, means for adjusting the lip of the flexible slice, separate means supporting the shoes of the secondary

35

30

40

pair thereof from said walls arranged for adjustment of said shoes up and down and towards and away from one another, and means supporting the deckle rulers from said structure arranged for transverse relative adjustment thereof relative to one another and longitudinally of said flexible slice.

6. Combined slice and deckle mechanism for the wire of a Fourdrinier paper machine comprising in combination, a structure having opposite transversely spaced vertical side walls and a stock inlet at the rear end thereof, a pair of elongated rear primary deckle shoes extending longitudinally forwardly of said inlet and being transversely adjustable towards and away from one another, a pair of elongated forward deckle rulers extending longitudinally of said side walls forwardly of said primary shoes and being transversely adjustable towards and away from one another, a pair of intermediate secondary shoes between said primary shoes and deckle rulers and being transversely adjustable towards and away from one another, a rigid slice extending transversely from wall to wall of said structure between adjacent ends of the primary and secondary shoes of the pairs thereof, a flexible slice extending transversely from wall to wall of said structure between adjacent ends of the secondary shoes and deckle rulers of the pairs thereof, separate mounting mechanisms connecting the primary and secondary shoes and the deckle rulers of the pairs thereof to said walls including means for adjusting the shoes and the rulers of the pair thereof towards and away from one another and longitudinally of said slices for alignment of said shoes and rulers to establish rearwardly and forwardly and between said slices a width of deckle inwardly of the ends of said slices.
